BURIAL VAULT COVER RECEIVING-AND-HANDLING APPARATUS

Walter Boehme, Forest Park, Ill.

Application August 2, 1946, Serial No. 687,938

4 Claims. (Cl. 27—1)

1

This invention relates to apparatus for handling concrete burial vaults and the box-like bases and covers thereof in cemeteries and in and adjacent to grave openings therein. Concrete burial vaults are heavy objects and the handling of them in cemeteries has heretofore required a great deal of heavy lifting by the workmen, often with serious injury to them.

An object of the present invention is to provide a novel but relatively simple and inexpensive apparatus for handling concrete burial vaults in cemeteries, and in and adjacent to a grave opening therein, in such a manner that the complete burial vault, as well as the box-like base and the cover thereof, may be readily handled by a crew of only two men and without necessitating any heavy lifting by the workmen so that danger to the workmen is thus eliminated.

An additional object of the invention is to construct the new burial vault handling apparatus in such a manner that it may readily be assembled and disassembled adjacent a grave opening so as to enable the cover and the box-like base of the vault to be handled in the manner described hereinafter.

An additional object of the invention is to construct the new burial vault handling apparatus in such a manner that the cover of a concrete burial vault may be handled in a novel manner in the use of the new burial vault handling apparatus so that the cover of the burial vault may be laid (prior to the burial service) in a position inclined relative to the vertical against the side of the mound of earth removed from the grave opening where it may be covered during the burial service by the same grass mat employed to cover the said mound of earth removed from the grave opening, and so that after the burial service the new burial vault handling apparatus may be reassembled and the burial vault cover then lowered into the grave opening upon the box-like base of the burial vault disposed therein.

A further object of the invention is to construct the new concrete burial vault handling apparatus in such a manner that it may be readily assembled in position of use at a grave opening and disassembled thereat by a crew of only two men.

Other and further objects of the present invention will be apparent from the following description and claims and are illustrated in the accompanying drawings which, by way of illustration, show preferred embodiments of the present invention and the principles thereof and what I now consider to be the best mode in which I have

contemplated applying these principles. Other embodiments of the invention embodying the same or equivalent principles may be used and structural changes may be made as desired by those skilled in the art without departing from the present invention and the purview of the appended claims.

In the drawings:

Fig. 1 is a side elevational view illustrating a preferred form of the new burial vault handling apparatus assembled at a grave opening and showing the box-like base and the cover of the burial vault assembled over a grave opening prior to removal of the cover from the box-like base of the vault and prior to lowering the said box-like base of the vault into the grave opening;

Fig. 2 is a view of the new burial vault handling apparatus assembled as in Fig. 1 but showing the cover of the burial vault in full lines after it has been removed from the box-like base of the vault and moved into a position above the mound of earth removed from the grave opening and showing it in dotted lines as it appears after it has been lowered onto the mound of earth removed from the grave opening. The box-like base of the vault is shown in full lines in this figure as it appears supported above the grave opening after the removal of the cover therefrom and is shown in dotted lines as it appears after having been lowered into the grave opening;

Fig. 3 is a side elevational view of the new burial vault handling apparatus, and of the assembled burial vault shown in Fig. 1, on line 3—3 in Fig. 1;

Fig. 4 is a fragmentary and elevational view on line 4—4 in Fig. 1 showing the burial vault cover guiding and clamping device embodied in the new burial vault handling apparatus for guiding the vault cover into, and for holding or clamping it in, an inclined position against one side of the mound of earth removed from the grave opening during the burial service;

Fig. 5 is a fragmentary sectional detail plan view on line 5—5 in Fig. 1 showing the hanger member and cooperating attachment plate embodied in the new burial vault handling apparatus for suspending one end portion of the horizontal carriage trackway or derrick beam from one of the upright supports or supporting standards therefor;

Fig. 6 is a sectional detail plan view, on line 6—6 in Fig. 1, illustrating the manner in which the other end portion of the horizontal carriage trackway or derrick beam embodied in the new burial vault handling apparatus is supported

upon the other upright support or supporting standard embodied in the new burial vault handling apparatus;

Fig. 7 is a top plan view on line 7—7 in Fig. 1 illustrating the combination cover guiding and clamping device by means of which the vault cover is guided into and retained during the burial service in an inclined position bearing against one side of the mound of earth removed from the grave opening;

Fig. 8 is a central sectional view of the combination cover guiding and clamping device shown in Fig. 7, on line 8—8 in Fig. 7;

Fig. 9 is a fragmentary vertical sectional view on line 9—9 in Fig. 6 illustrating the manner in which one end portion of the horizontal carriage trackway or derrick beam is mounted on one of the upright supports or supporting standards therefor;

Fig. 10 is an enlarged detail view on line 10—10 in Fig. 1 illustrating a chain spreader plate embodied in the new concrete burial vault handling apparatus for spreading the chains necessary to lift the cover and the box-like base of a concrete burial vault during the operation of raising and lowering the cover and the box-like base or body of the vault; and

Fig. 11 is an end elevational view of the chain spreader plate and the spreader chains used in conjunction therewith in the new concrete burial vault handling apparatus.

A preferred embodiment of the new concrete burial vault handling apparatus is shown in the drawings, wherein it is generally indicated at 15, and comprises two upright supports or supporting standards 16 and 17 which cooperate to support a horizontally extending carriage trackway or derrick beam 18 extending therebetween. The new concrete burial vault handling apparatus also includes a chain and pulley unit or block and tackle unit 19 which is suspended from a roller-bearing traveling carriage 20 which is movable along the trackway 18, and the new burial vault handling apparatus also includes a combination cover guiding and clamping unit 21; all of which parts or units of the new burial vault handling device will be described in detail hereinafter.

As shown in the drawings, the upright support of supporting standard 17 includes a pair of tubular steel supporting legs 22 and 23 which are arranged in a V-shaped formation relative to each other (Fig. 3). Each of these supporting legs 22 and 23 has a flattened foot portion 25 which may be attached, as by means of a bolt 26, to a plank or like base support 27 which may be disposed upon the ground 28 of a cemetery at one side of a grave opening 29 therein.

As is best shown in Fig. 3, each of the supporting legs 22 and 23 also has a flattened upper end portion 30 and these flattened upper end portions 30 of the legs 22 and 23 are disposed parallel to but spaced slightly from each other and are interconnected by a horizontally extending nut-bearing threaded bolt 31, and nut 24 thereon. The bolt 31 extends through suitable openings formed in the flattened upper end portions 30 of the two legs 22 and 23 of the supporting standard or upright support 17 and the two legs 22 and 23 are arranged in a V-shaped formation (Fig. 3).

As shown in Figs. 1 and 5, the horizontally extending carriage trackway or derrick beam 18 is generally T-shaped and includes a centrally arranged body portion or central web 32, a pair

of laterally extending horizontal top flanges 33, and a pair of laterally extending horizontal bottom flanges 34, all of which are integral with the central web 32. A metal plate 35 is mounted on one end portion of the top flanges 33 of the carriage trackway or derrick beam 18, as by means of bolts 36. As shown in Fig. 5, the plate 35 has an elongated slot 37 formed therein outwardly of the adjacent end wall 38 of the horizontal carriage trackway or derrick beam 18, and the plate 35 also has a second slot 39 formed in the outer end portion thereof, said notch 39 opening outwardly at the outer end edge 40 of the plate 35. As is also shown in Fig. 5, the slots 37 and 39 are elongated with their long axes extending parallel to the central web 32 of the carriage trackway or beam 18.

The new burial vault handling apparatus includes a metal hanger member 41 which has an annular upper end portion 42 which is swingingly mounted on the bolt 31 which extends between the flattened upper end portions 30 of the legs 22 and 23 of the upright support or supporting standard 17. The metal hanger member 41 has a hook-shaped lower end portion 43 and in the use of the said hanger member 41 the main extent or body portion 41 thereof extends through the end slot 39 in the plate 35 and the hook-shaped lower end portion 43 thereof extends upwardly into the inner slot 37 in the plate 35. In this manner one end portion of the horizontal carriage trackway or derrick beam 18 is thus suspended by the hanger member 41 from the bolt 31 which extends between the flattened upper end portions 30 of the legs 22 and 23 of the upright support or supporting standard 17. The advantages incident to the use of this arrangement will be described hereinafter.

The upright support or supporting standard 40 16 comprises a cylindrical pipe-like pedestal 44 which has an enlarged annular base flange 45 at its lower end, which is attached in any suitable manner, as by being bolted, to a plank 46 which is adapted to be mounted on the ground 28 of a cemetery adjacent the grave opening 29 but at the opposite side of the grave opening 29 from the side at which the upright support or supporting standard 17 is mounted (Figs. 1 and 2).

The upright support or supporting standard 50 16 also includes an upper cylindrical pipe-like member 47, the lower end portion of which is telescopically inserted into the pipe-like cylindrical pedestal 44 of the upright supporting unit or supporting standard 16. The upper end portion 55 of the pipe 47 is exteriorly threaded, as at 48, and an internally threaded sleeve 49 is mounted on the threaded upper end portion 48 of the pipe-like member 47. The sleeve 49 has a U-shaped head 50 formed integrally therewith and this head 50 includes a pair of spaced parallel arms 51 which are interconnected by an interconnecting or bight portion 52, and the threaded sleeve 49 has a flange 53 formed thereon at its upper end (Fig. 9). As shown in Figs. 65 1, 2, 6 and 9, one end portion of the horizontal carriage trackway or derrick beam 18 is mounted between the parallel arms 51 of the member 50 and is supported therebetween upon the flanged upper end portion 51 of the threaded sleeve 49.

The combination vault cover guiding and clamping device 21 is associated with the cylindrical pedestal 44 and includes a supporting frame 53 which comprises a pair of spaced metal rods 54 which are interconnected at their lower ends by an offset interconnecting or bight por-

tion 55 (Figs. 7 and 8). Each of the arms 54 has a hook-shaped upper end portion 56 and each of these hook-shaped portions 56 is pivotally mounted upon a laterally extending arm 57 of a bracing rod which is formed as a part of a bracing unit 53. The spaced metal arms 59 of the bracing unit 53 are welded at their upper ends, as at 60, to the cylindrical pedestal 44, and the lower end portions 61 of these arms 59 are welded, as at 62, to a metal plate 63 which is attached by bolts 64 to the supporting plank or base 46 (Fig. 4).

The combination cover guiding and clamping device 21 also includes a metal plate 65 which is attached to the upper portions of the arms 54 thereof in any suitable manner, as by welding, and the said combination cover guiding and clamping device 21 also includes a second metal plate 66 which is attached to the lower portions of the rods 54 in any suitable manner, as by welding, or the like. As shown in Figs. 7 and 8 the two plates 65 and 66 are arranged upon the same side of the rods 54 and, as will be explained hereinafter, the plates 65 and 66 cooperate with the rods 54 of the frame 53 to provide a cradle for the reception of the cover 86 of a concrete burial vault 87.

The combination cover guiding and clamping device 21 includes a clamping handle member 67 which has a threaded portion 68 which is threaded into a nut 69 which is welded or otherwise fastened to the offset lower end portion 55 of the frame 53 of the vault cover guiding and retaining unit 21. A nut 70 is mounted on the threaded portion 68 of the clamping handle member 67 and a washer or disc 71 is mounted on the threaded portion 68 of the clamping handle member 67 adjacent the nut 70. A coiled spring 72 is mounted on the said threaded portion 68 of the clamping handle member 67 between the nut 69 and the washer 71, this coiled spring exerting a binding action or frictional drag on the threaded portion 68 of the clamping handle member 67 to prevent the latter from turning freely in the nut 69.

The traveling carriage unit 20 includes a supporting frame 73 on which pairs of spaced rollers 74 are mounted and these rollers 74 ride upon the upper surfaces of the bottom flanges 34 of the carriage trackway or derrick beam 18 on opposite sides of the center portion 32 thereof.

The block and tackle unit 19 is suspended by a hook 75 from the frame 73 of the traveling carriage unit 20 and includes a block or pulley 76 and a chain 77 which works therearound, the chain 77 having a hook 78 attached to the lower end thereof.

The new burial vault handling apparatus includes a chain spreader plate 79 (Fig. 10) having a centrally arranged notch 80 formed therein for the reception of the hook 78 which is mounted on the lower end portion of the chain 77. The chain spreader plate 79 also has a pair of chain-receiving openings formed therein and each of these chain-receiving openings 81 has a restricted or narrow slot 82 formed at one side thereof in the chain spreader plate 79.

The new burial vault handling apparatus also includes a plurality of spreader chains 83, each of which has an elongated metal hook 84 attached thereto at one end thereof. Each of these metal hooks 84 is adapted to be engaged with U-shaped clevises 85 which are anchored in the concrete cover 86 of a concrete burial vault, such as that indicated at 87, and which includes a

box-like base 88. There are customarily four of these U-shaped clevises anchored and arranged in a rectangular pattern in the cover 86 of a concrete burial vault 87 and, similarly, there are likewise customarily four U-shaped clevises 91 (Fig. 20) anchored in a rectangular pattern in the bottom of the box-like base or body 88 of concrete burial vault 87.

The use and operation of the new burial vault handling apparatus are as follows: The pedestal 44 of the upright support 16 and the bracing rods 59 therefor are arranged upon their supporting base or plank 46 at one side of the area in which the grave 29 is to be dug in the ground 28 of a cemetery and as the earth 90 is removed from the grave opening 29 it is piled in a mound about the pedestal 44 of the upright supporting standard 16.

After the grave opening 29 has been dug planks 89 may be laid thereacross, whereupon the concrete burial vault 86 which is to be lowered into the grave opening 29 is laid upon the planks 89, being delivered to the cemetery by means of a truck or the like. The assembly of the new burial vault handling apparatus 15 may then be completed as follows: The lower end portion of the pipe-like member 47 of the supporting standard 15 is telescopically inserted into the pedestal 44 and the sleeve 49 threaded thereon. The other upright support or supporting standard 17 may then be erected by mounting the flattened lower end portions 25 of the supporting legs 22 and 23 upon a suitable supporting base, such as the plank 21. The bolt 31 may then be inserted through suitable openings provided in the flattened upper end portions 30 of the legs 22 and 23 and through the annular upper end portion 42 of the hanger member 41 so that the hanger member 41—43 is thus suspended upon the bolt 31 between the flattened upper end portions 30 of the legs 22 and 23 of the upright support or supporting standard 17. The nut 24 may then be threaded onto the outer end portion of the bolt 31 so as to hold the legs 22 and 23, the bolt 31 and the hanger member 41 in assembled relationship.

The traveling carriage 20 may then be mounted in position on the horizontal trackway or derrick beam 18, with the rollers 74 thereof riding upon the lower flanges 34 of the trackway or beam 18. One end portion of the said horizontal trackway or beam may then be raised and inserted into position between the spaced parallel arms 51 of the threaded sleeve 49 which is mounted on the threaded upper end portion 48 of the pipe-like upper member 47 of the supporting standard 15. The trackway or beam 18 may then be manipulated upon the sleeve 49 as a pivot so as to position the metal plate 35 attached thereto in such a manner that the main extent or body of the hanger member 41 will enter the outer slot 39 in the plate 35 and the hook-shaped portion 43 of the hanger member 41 will enter into the inner slot 37 in the metal plate 35 (Fig. 5).

The block and tackle unit 19 may then be assembled with the traveling carriage 20 by engaging the hook 75 between the side walls of the frame of the carriage 20 in the manner shown.

The hook 78 which is attached to the lower end of the chain 77 of the block and tackle unit 19 may then be inserted in the central notch 80 in the chain spreader plate 79 and the spreader chains 83 inserted through the holes 81 in the chain spreader plate 79 and thence moved into the restricted or narrow slots 82 so as to hold the

chains 83 in assembled relationship with the chain spreader plate 79 and with the hooks 84 which are attached to the chains 83 adjusted to suitable lengths to enable them to reach from the chain spreader plate 79 to the four U-shaped clevises 85 which are anchored in the concrete of the vault cover 86 in a rectangular pattern.

The combination cover guiding and clamping unit 21 may then be assembled in operative relation with the pedestal 44 of the supporting standard 15 by slipping the hook-shaped upper end portions 56 of the arms 54 of the frame 53 of the unit 21 over the laterally extending arms 57 of the bracing rods 59 so that the said hook-shaped upper end portions of the arms 54 will pivot on the laterally extending arms 57 of the bracing rods 59.

Accordingly, after the parts have thus been assembled and properly adjusted, the elongated hooks 84 on the chains 83 may be inserted through the clevises 85 in the cover 86 of the concrete burial vault 87. The chain 77 of the block and tackle unit 19 may then be manipulated to raise the cover 86 off and above the box-like base 88 of the concrete burial vault 87 whereupon the said cover 86 may be moved laterally from the position in which it is shown in Fig. 1 into the position in which it is shown in full lines in Fig. 2, whereupon the combination cover guiding and clamping unit 21 may then be raised into horizontal position. This is accomplished by pivoting the hook-shaped upper end portions 56 of the arms 54 of the frame 53 of the combination cover guiding and clamping unit 21 on the laterally extending arms 57 of the bracing rods 59. However, after the said combination cover guiding and clamping unit 21 has thus been moved into horizontal position the cover 86 of the burial vault 87 may be lowered onto the said combination cover guiding and clamping unit so that it rests upon the flat plates 65 and 66 thereof which thus provide a cradle for the cover 86.

During this operation the clamping handle member 67 is rotated in the nut 69 so that the main extent of the said clamping handle member 67 lies clear of and outside the periphery of the frame 53 of the unit 21. After the vault cover 86 has thus been lowered onto the guiding and clamping unit 21 the clamping handle member 67 may be moved into effective position above the top of the vault cover 86 and into the position in which it is shown in full lines in Fig. 2.

The vault cover 86 may then be lowered by manipulating the chain 77 of the block and tackle unit 19 whereupon the cover 86 of the burial vault thus clamped to the combination guiding and clamping unit will be lowered therewith with the hook-shaped upper end portions 56 of the arms 54 of the frame 53 pivoting upon the laterally extending arms 57 of the bracing members 59.

In this manner the vault cover 86 is lowered into the position in which it is shown in dotted lines in Fig. 2, whereupon the hooks 84 are removed from the clevises 85 in the vault cover 86, the chain 77 of the block and tackle unit 19 adjusted as to height and moved with the carriage 20 back into position above the box-like base 88 of the burial vault 87. The chain 77 of the block and tackle unit 19 may then be manipulated so as to lower the hooks 84 downwardly into the box-like base 88 of the burial vault 87 wherein the hooks 84 may be engaged with the four clevises 91 which are anchored in a rectan-

gular pattern in the bottom of the box-like base 88 of the burial vault 87.

The box-like base 88 of the burial vault 87 may then be raised above the planking 89 and the planking 89 removed, whereupon the said box-like base 88 of the burial vault 87 may be lowered into the grave opening 29 and in which position it is shown in dotted lines in Fig. 2. The hooks 84 may then be disengaged from the clevises 91 in the bottom of the box-like base 88 of the burial vault 87 and the hooks 84 raised up out of the grave opening 29 by manipulating the chain 77 of the block and tackle unit 19.

The new burial vault handling apparatus 10 may thereupon be disassembled. This may be accomplished by unlatching the hook 75 of the block and tackle unit 19 from the traveling carriage 73, raising the horizontal carriage trackway or derrick beam 18 so as to raise the metal plate 35 attached to one end portion thereof out of engagement with the hook-shaped portion 43 of the hanger member 41, removing the other end portion of the trackway or beam 18 from between the arms 51 of the head 50 of the threaded sleeve 49, removing the bolt 31 from engagement with the flattened upper end portions 20 of the legs 22 and 23 of the supporting standard 17, detaching the flattened lower end portions or feet 25 of the supporting legs 22 and 23 from the supporting base or plank 27, and then sliding the lower end portion of the member 47 out of the cylindrical pedestal 44.

It will be noted, however, that in thus disassembling the new burial vault handling apparatus the pedestal 44 and the bracing rods 59 and the combination cover guiding and clamping unit 21, with the vault cover 86 clamped thereon, are allowed to remain in the position in which these parts are shown in Fig. 1, with the burial vault cover 86 clamped thereon in the position in which it is shown in dotted lines in Fig. 2. The pedestal 44, bracing rods 59, the combination cover guiding and clamping unit 21, and the vault cover 86 clamped thereon may be covered by a conventional and the same grass mat which is likewise employed for obscuring the mound of earth 90 during the burial service but which is, of course, removed after the burial service.

After the burial service the new burial vault handling apparatus may again be assembled, in the manner described hereinbefore.

The traveling carriage 20 and the block and tackle unit 19 may then be moved into a position above the concrete burial vault cover 86 which is at this time disposed in the position in which it is shown in dotted lines in Fig. 2. The hooks 84 may then be engaged in the clevises 85 in the vault cover 86 and the clamping handle member 67 rotated out of engagement with the vault cover 86. The vault cover 86 may be raised by manipulating the chain 77 of the block and tackle unit 19 which may then be moved with the traveling carriage 20 along the horizontal trackway 18 until the vault cover 86 comes into a position above the grave opening 29. The vault cover 86 may then be lowered into the grave opening 29 and onto the box-like base 88 of the burial vault 87 by manipulating the chain 77 of the block and tackle unit 19. After the vault cover 86 has thus been lowered into the grave opening 29 and onto the box-like base 88 of the vault 87 so as to seal the casket therein the hooks 84 may be disengaged from the clevises 85 in the vault cover 86 and the chain 77 of the block and tackle unit 19 again manipulated to raise the

hooks 84 and the chains 83 and the spreader plate 79 up out of the grave opening 29. The combination cover guiding and clamping unit 21 may then be removed by slipping the hook-shaped upper end portions 56 of the arms 54 thereof off the laterally extending arms 57 of the bracing rods 59.

The new burial vault handling apparatus 15 may then again be disassembled, in the manner hereinbefore described, whereupon the mound of earth 90 removed from the grave opening may be removed from around the pedestal 44 and shovelled into the grave opening 29 upon the thus assembled burial vault 87 therein. The pedestal 44, the supporting base or plank 46 therefor, and the bracing rods 59 may then be moved, with the other parts of the new burial vault handling apparatus, to another grave lot for further use.

It will be noted that the threaded sleeve 49 and the supporting head 50—51—52 carried thereby will turn in a horizontal plane upon the threaded upper end portion 48 of the tubular upper member 47 of the upright supporting unit or standard 17 so as to enable the trackway or beam 18 and the plate 35 carried thereby to be aligned for suspension from the hanger member 41—43.

It will be noted that the clamping handle member 67 may be rotated (clockwise, Fig. 7) into an ineffective position in which the main extent thereof lies parallel to the offset lower end portion 55 of the frame 53 so as to permit the burial vault cover 86 to be inserted onto and removed from the combination guiding and clamping unit 21. The coil spring 72 prevents free swinging of the clamping handle member 67 and holds the same in any desired adjusted position.

It will thus be seen from the foregoing description, considered in conjunction with the accompanying drawings, that the present invention provides a new and improved but simple concrete burial vault handling apparatus which has the desirable advantages and characteristics, and which accomplishes its intended objects, including those hereinbefore pointed out and others which are inherent in the invention.

I claim:

1. A concrete burial vault cover-receiving and supporting apparatus comprising a supporting pedestal adapted to be arranged at one side of a grave opening, a burial vault cover-receiving and supporting member pivotally mounted upon the said supporting pedestal for receiving a burial vault cover and supporting the same, and man-

ually operable means for releasably clamping a burial vault cover upon the said burial vault cover-receiving and supporting member and mounted for pivotal movement therewith relative to the said supporting pedestal whereby the said burial vault cover may be supported by the said burial vault cover-receiving and supporting member at a preselected angle relative to the vertical when the said burial vault cover-receiving and supporting member bears against a suitable bearing surface.

2. A concrete burial vault cover-receiving and supporting member as defined in claim 1 in which the said manually operable clamping means is movably mounted upon the outer and normally lower end portion of the said burial vault cover-receiving and supporting member.

3. A concrete burial vault cover-receiving and supporting member as defined in claim 1 in which the said manually operable clamping means includes a manually operable clamping handle member rotatably mounted upon the said burial vault cover-receiving and supporting member and having a portion adapted to be manually moved into and out of position above the upper surface of the said burial vault cover so as to releasably clamp the said burial vault cover upon the said burial vault cover-receiving and supporting member.

4. A burial vault cover-receiving and supporting member as defined in claim 1 which includes means for bracing the said supporting pedestal, and in which the said burial vault cover-receiving and supporting member is pivotally mounted at one side thereof upon the said bracing means and has the said manually operable clamping means rotatably mounted thereon at a side thereof which is opposite the said first-named side thereof.

WALTER BOEHME.
